UNITED STATES PATENT OFFICE.

HENRY GIEBEL, OF NEW YORK, N. Y., ASSIGNOR TO THOMAS WILSON & CO. INC., OF NEW YORK, N. Y., A CORPORATION OF NEW YORK.

DESIGN FOR LACE.

Application filed February 28, 1923. Serial No. 5,307. Term of patent 3½ years.

To all whom it may concern:

Be it known that I, HENRY GIEBEL, a citizen of the United States, residing at New York, in the county of Kings and State of New York, have invented a new, original, and ornamental Design for Laces, of which the following is a specification, reference being had to the accompanying drawing, forming part thereof.

The figure is a view of the lace, showing my new design.

I claim:—

The ornamental design for the lace, as shown.

HENRY GIEBEL.
